TWIRLING BATON

Donald L. Sartell, 328 Seminole Road,
Janesville, Wis. 53545

Filed Jan. 20, 1971, Ser. No. 108,245

Term of patent 14 years

Int. Cl. D21—01

U.S. Cl. D34—5

FIG. 1 is a side elevational view of the baton, showing my new design;

FIG. 2 is an end view of the baton, as seen looking downwardly on FIG. 1; and

FIG. 3 is an end view of the other end of the baton, as seen looking upwardly on FIG. 1.

I claim:

The ornamental design for a twirling baton, as shown.
